ABSTRACT

The present invention discloses a container sorting system capable of increased sorting efficiency. The present invention discloses a device in which the distance is shortened between detection and ejection of containers being sorted by reflective infrared radiation, transmission infrared radiation, or both. The present invention also includes a method of operating such device.

BACKGROUND OF THE INVENTION

As the general public continues to increase its willingness to recycle, there are a variety of reasons that would lead to the desire for a container sorting system having improved efficiency. Currently available sorting systems are plagued with many shortcomings. Traditional sorting systems use sensing devices which are bulky and have traditionally been configured to sort materials with a conveyor belt as a backdrop. Sensing systems in this configuration receive signals from the conveyor belt as well as from the items to be sorted which can complicate the identification of items. The traditional configuration of sorting systems also has resulted in a significant distance being present between the sensing region and the sorting region of a system. Given that many of the items being sorted are light weight cylindrically shaped bottles, one can imagine the movement of such individual items on the surface of a rapidly moving conveyor belt. Unfortunately, such lateral movement and variations in acceleration result in a complicated and hard to predict path of travel for such an item as it passes from a sensing region over a significant distance to a sorting region. If the item does not reach the sorting region at the time and location at which it is expected, then the sorting system has failed. The result is that sorting is not being performed in an efficient manner.

SUMMARY OF INVENTION

Disclosed herein is a container sorting system capable of improved sorting efficiency. As further described herein, the present invention eliminates interference signals from a conveyor belt and also allows for the distance between the sensing region and ejection region of the system to be only a minimal distance. Also disclosed herein is a method of sorting containers by use of the disclosed device.

The sorting device for sorting materials according to composition includes an infrared radiation source, a conveyor, wherein the conveyor has a discharge end, an infrared radiation sensing system positioned to receive and detect infrared radiation reflected off a sample while the sample is located

immediately off the discharge end of the conveyor and is irradiated with infrared radiation from the infrared radiation source, a first processing system operationally connected to the infrared radiation sensing system so that the detected infrared radiation signals are analyzed to determine composition of the sample, an ejection system positioned immediately downstream from the infrared radiation sensing system, a second processing system operationally connected to the ejection system so that sample having certain composition 5 may be ejected out of the flow path by the ejection system, and a receiving station positioned to receive ejected sample. In certain embodiments, the infrared radiation sensing system is located a minimal distance downstream from the discharge end of the conveyor. In other embodiments, the ejection system is located a minimal distance downstream from the infrared radiation sensing system. In yet other embodiments, the first processing system and the second processing system are combined into a single processing system. Also disclosed herein is a sorting device for sorting materials according to 10 composition which includes an infrared radiation source, a conveyor, wherein the conveyor has a discharge end, an infrared radiation sensing system positioned to receive and detect infrared radiation reflected off a sample while the sample is located immediately off the discharge end of the conveyor 15 and is irradiated with infrared radiation from the infrared radiation source, a processing system operationally connected to the infrared radiation sensing system so that the detected infrared radiation signals are analyzed to determine composition of the sample, an ejection system operationally 20 connected to the processing system so that a sample having a certain composition may be ejected out of the flow path, wherein the ejection system is positioned immediately downstream from the infrared radiation sensing system, and a receiving station positioned to receive ejected sample. In 25 certain embodiments, the device further includes a transmission infrared radiation source positioned so that the infrared radiation sensing system receives and detects infrared radiation transmitted through the sample while the sample is located immediately off the discharge end of the conveyor 30 and is irradiated with infrared radiation from the transmission infrared radiation source.

Also disclosed herein is a method of sensing and sorting materials according to composition which includes providing a sample, placing the sample on a conveyor having a discharge end, placing the sample in an infrared radiation sensing region, wherein the infrared radiation sensing region is located immediately off the discharge end of the conveyor, irradiating the sample to be sorted with infrared radiation in the sensing region, detecting infrared radiation signals 45 reflected off the sample while the sample is in the sensing region, analyzing the infrared radiation signals to determine composition of the sample, and energizing at least one air ejector of an air ejection array, wherein the air ejection array is located immediately downstream from the infrared radiation sensing region. In certain embodiments, the infrared radiation sensing region is located at a minimal distance from the discharge end of the conveyor. In other embodiments, the air ejection array is located at a minimal distance downstream from the infrared radiation sensing region. In still other embodiments, the method further includes detecting infrared radiation signals transmitted through the sample while the sample is in the sensing region.

Accordingly, one object of the present invention is to provide a sorting system having only a minimal distance between the sensing region and the ejection region.

Another object of the present invention is to provide a sorting system having an improved sorting efficiency. Yet

another object of the present invention is to provide a sorting system that minimizes interference signals from a conveyor belt surface.

Still another object of the present invention is to provide a method of sorting containers that does not require regular cleaning of a conveyor belt surface.

Yet another object of the present invention is to provide a method of sorting containers that does not pose a fire hazard to the facility in which the sorting system is located.

Still another object of the present invention is to provide a sorting system having the capability to sort with reflected infrared radiation, transmission infrared radiation, or both.

BRIEF DESCRIPTION OF THE DRAWINGS

FIG. 1 is a schematic diagram of a side view of a currently available sorting system. Shown therein is the traditional positioning of a sensing region on a conveyor which is separated by a significant distance ("D") from the ejection region.

FIG. 2 is a schematic diagram showing a top view of the sorting system shown in FIG. 1. Shown therein is a flaw of the traditional system in that the distance between the sensing region and the ejection region is long enough to allow an item being sorted to move along its actual path (solid arrow) rather than its expected path (dashed arrow) such that the item is not properly sorted. The shaded ejector represents the ejector that was fired to sort the item.

FIG. 3 is a schematic drawing of a side view of an embodiment of the sorting system disclosed herein. Shown therein is a conveyor transporting a sample to be sorted in the direction of the arrow. The vertical dashed lines represent the locations of the sensing region and the ejection region, being separated by a distance ("D"). The sensing region is immediately off the discharge end of the conveyor. The ejection region is only a matter of inches away from the sensing region.

FIG. 4 is a schematic drawing of a top view of the embodiment of the invention shown in FIG. 3. Phantom lines are used to show the boundary of the conveyor and the ejectors which are located beneath the infrared radiation sensing system. Shown therein is an actual path of travel (solid arrow) of an item being sorted and an expected path of travel (dashed arrow) of that same item. The invention disclosed herein provides an improved sorting efficiency because of the small distance between the sensing region and the ejection region which allows for a single ejector to be fired (shaded ejector) to correctly eject an item even though the item's actual travel path and its expected travel path are not the same.

FIG. 5 is a schematic drawing of a side view of another embodiment of the sorting system disclosed herein. Shown therein is a conveyor transporting sample to be sorted. The sensing region is immediately off the discharge end of the conveyor. This embodiment of the invention has a transmission infrared radiation source located beneath the discharge end of the conveyor in addition to the reflective infrared radiation source of the embodiment shown in FIG. 3. The ejection region is positioned to be only a matter of inches away from the sensing region, in relation to the sample flow path, which is represented by the direction of the arrow on the conveyor.

DESCRIPTION OF THE PREFERRED EMBODIMENTS

The present invention is an infrared radiation sorting system that overcomes the flaws of currently available reflective infrared sorting systems. The infrared radiation sorting system, referred to as the system 10, includes an infrared radia-

tion source 12, conveyor 14, infrared radiation sensing system 16, first processing system 18, second processing system 20, an ejection system 22, and a receiving station 24. Also disclosed herein is a method of using the system 10 to more efficiently sort materials according to composition.

Currently available material sorting systems that operate in the near infrared range (1.0-2.5 microns) and sense infrared radiation reflected off a material item (such as a plastic bottle) operate in a configuration where the sensing system is positioned over a conveyor 14 belt, as best seen in FIG. 1. In this configuration samples 28 on the conveyor 14 pass under the sensing system 16 where they are irradiated with infrared radiation 36 from an infrared radiation source 12 and the sensing system 16 monitors the infrared radiation reflected 38 off the sample 28. Currently available systems are not desirable due to the distance between the infrared radiation sensing region and ejection region. That is, an item to be ejected must travel the distance ("D") between detection in the sensing region and ejection location. Typically this distance can be several feet (e.g. 3-4 feet). An item to be ejected can roll, bounce, or otherwise be disturbed when being conveyed the distance from detection to ejection. Such disturbances can change the position and/or speed of the item causing problems in ejection. If the item is rolling then it can be conveyed at a speed different (generally slower) than the conveyor 14 belt speed causing it to arrive at the ejection location before or after the ejector is fired since the processor system 19 expects the item to be conveyed at the speed of the conveyor 14.

Another disadvantage of current systems is that if the conveyed item has a lateral velocity component then it can move into an adjacent region on the conveyor 14 belt upon arrival at the ejection location and be missed by the firing of the air ejectors in the ejection channel directly downstream along the item expected path of travel determined at the time of detection in the sensing region. Stated another way, as best seen in FIG. 2, there is an actual path of travel (shown by a solid arrow) of an item which differs from the expected path of travel (shown by a dashed arrow). The sorting system fires an ejector 23 at the expected time/location in order to separate the item by giving it a trajectory path 21 over the splitter 40. However, because the actual path of travel of the item to be ejected differs, the item passes over the ejector not fired 25. Referring back to FIG. 1, the significant distance between the location of detection and location of ejection results in less than optimal sorting.

Still another disadvantage of traditional sorting systems in recycling plants is that there is typically a build up of foreign materials (dirt, grime, liquids, bottle labels, etc.) that occurs on a conveyor 14 belt during operation. This build up of foreign materials can interfere with the reflected infrared radiation signals 38 being received by the infrared radiation sensing system 16 and degrade sorting performance. Therefore, it is common for the belt surface to require periodic cleaning as a maintenance item—often once per shift. This cleaning requires manpower and time and is a maintenance cost. Also, in some sorting scenarios it is advantageous to determine color of item along with its infrared radiation signature. Many items to be sorted are transparent such as those made from polyethylene terephthalate (PET) or polystyrene (PS). The transparent item may have a color to it such as a green, blue, or amber PET bottle (for example). This color of a transparent item can be difficult for a sensing system 16 to distinguish if the item is on a conveyor 14 belt surface since the belt surface can be seen through the transparent item. For example, it can very hard to "see" the color of a PET bottle on a black conveyor 14 belt surface when lighted from above, especially "clear" bottles or lightly colored bottles such as

light blue bottles. Additionally the build up of foreign materials on the belt can interfere with the color analyses degrading color sorting performance. Finally, the infrared radiation source **12** used in these systems is typically one or two banks of highly intense tungsten halogen lamps, positioned on the upstream and/or downstream sides of the infrared radiation sensing system **16**, as shown in FIG. 1, with a very bright light output that has a strong near infrared radiation presence in the radiation spectrum. These lighting systems can quickly cause a large heat build-up on the conveyor **14** belt surface and any items present if the conveyor **14** belt is stopped with the belt surface area in the irradiated region stationary while the lamps are energized. There have been reports of fires being started in recycling facilities by such circumstances.

Referring now to FIG. 3, there is an embodiment of the present invention. Shown there is a schematic diagram of a side view detailing the conveyor **14**, which has a discharge end **26**, that is moving in the direction of the arrow. Sample **28** is shown moving on the conveyor **14**. After passing the discharge end **26** of the conveyor **14**, the sample **28** is positioned to receive infrared radiation **36** from the infrared radiation source **12**. The spectral characteristics of the reflected infrared radiation signal **38** contains information specific to the material samples **28** irradiated. Commercially available software to analyze infrared signals is available from LLA Instruments GmbH, Berlin, Germany. Infrared radiation sources **12** suitable for this use can be obtained from General Electric Company, Fairfield, Conn., and are well known and generally commercially available in the art. Infrared radiation is reflected **38** off the sample **28** and detected by the infrared radiation sensing system **16**. Infrared radiation sensing systems **16** may be obtained from LLA Instruments GmbH, Berlin, Germany, and are well known and generally commercially available in the art. The infrared radiation sensing system **16** is operationally connected to the first processing system **18**. One of ordinary skill in the art is familiar with the manner of operationally connecting components in detection systems as disclosed herein. All such wires, cables, and the like, needed for such operational connectivity are well known in the art and generally commercially available. Regarding each component of the system **10** disclosed herein, operational connectivity includes any connections necessary for power, data or information transfer, or the like, for the operation of the specific device. One of ordinary skill in the art is familiar with such types of connections. Note that U.S. Pat. No. 6,610,981 issued to Sommer, Jr. on Aug. 26, 2003 is hereby incorporated by reference in its entirety.

As further described below, the ejection system **22** is momentarily activated to eject an item selected for ejection after a delay time that depends upon the conveyor belt speed and the distance *D* between the sensing region and the ejection location. A typical application is the sorting of containers in a mixed recyclable container stream. The first processing system **18** is a microprocessor. Such a microprocessor may be a single microprocessor or a system of multiple microprocessors linked together to share computational tasks to enable high speed data processing. A suitable multiple microprocessor system is the Barcelona-HS available from Spectrum Signal Processing, Burnaby, Canada. The first processing system **18** is also operationally connected to a second processing system **20**. Briefly, the ejection system **22** is controlled by the second processing system **20** which is responsive to information received from the first processing system **18**. The second processing system **20** signals the ejection system **22** through connections **32** to selectively energize appropriate air ejectors within the ejection system **22** to deflect by short air blasts selected materials from the sample

28 flow. That is, the first processing system **18** provides and receives control signals to/from the infrared radiation sensing system **16** over an electrical/data connection **30**. Data from the infrared sensing system **16** flows to first processing system **18** over connections **30** through an analog-to-digital conversion card so that digital data is presented to first processing system **18**. A materials classification and sorting algorithm, or software, executes within the first processing system **18** to process the digital data and utilizes computer memory for storing data and accessing data during execution. According to results derived through executing the algorithm the second processing system **20** signals the ejection system **22**, for example a bank of solid state relays such as those supplied by Opto22, Temecula, Calif., through DIO module to energize selected air ejectors within air ejector array of the ejection system **22**. In practice it may be that the tasks performed by the first processing system **18** and the second processing system **20** may be performed by a single processor or a system of multiple processors. As best seen in FIG. 4, the ejection system **22** is positioned across the width of the trajectory path **42** of materials discharged off the end **26** of conveyor **14** and is an array of high speed air ejectors, such as the L2 series supplied by Numatics, Highland, Mich. The ejected item trajectory **42** results in the item passing over the splitter **40** and landing in a receiving station **44**. In certain embodiments, a receiving station **44** may be an appropriately sized container for holding the sorted materials or a conveying system to remove ejected items from the sorting system **10**. The materials of construction of the receiving station **44** are readily commercially available and well known in the sorting industry. Also, manufacturers are readily available for the manufacture of such goods, according to the known methods of manufacture within the industry. The user of the sorting system may chose through a standard control interface (not shown) alternate ejection settings, as would be known to those of ordinary skill in the art.

Still referring to FIG. 4, there is shown a schematic diagram of a top view of the system **10** disclosed herein. As shown therein, in certain embodiments of the invention, the infrared radiation sensing system **16** is positioned to receive reflected **38** infrared radiation as the sample **28** is located immediately off the discharge end **26** of the conveyor **14**. In other embodiments, the infrared radiation sensing system **16** is positioned to receive reflected **38** infrared radiation as the sample **28** is located a minimal distance downstream from the discharge end **26** of the conveyor **14**. A minimal distance is from about one inch to about six inches. In another embodiment, a minimal distance is about two inches. Still referring to FIG. 4, the solid arrow represents the actual path of travel of a specific item, which is in contrast to the dashed line which represents the expected path of travel of the specific item. The visual shows that a shorter distance between infrared radiation sensing and ejection allows for a single ejector **34** to be in both paths. That is, even if the expected path of travel of an item differs from the actual path of travel, when the infrared radiation sensing and ejection occur within a minimal distance, the two paths do not have an opportunity to diverge in such a short distance. Accordingly, the single ejector **34** is fired and properly ejects the item for which paths of travel are shown. If the ejector system **22** is located a further distance from the position at which infrared radiation is detected, then there is not a single ejector that is on both the actual and expected paths of travel.

Referring now to FIG. 5, there is shown a schematic diagram of a side view of another embodiment of the present invention. Shown therein is a system **10** additionally having a transmission infrared radiation source **48** located in line with

the infrared radiation sensing system **16**. The system **10** is capable of detection by transmission infrared radiation, reflection infrared radiation, or both. Such an additional transmission infrared radiation source **48** enables operating in transmission mode where a transmitted infrared radiation signal **50** processed by the infrared radiation sensing system **16** passes through the sample **28** being sensed. Such transmission sensing can be advantageous for identifying composition of transparent/translucent items such as PET bottles, and "natural" (i.e., not pigmented) HDPE (high density polyethylene), PP (polypropylene), and PS (polystyrene) materials since infrared radiation passing through a material can exhibit superior absorption at the material's signature frequencies than for reflected infrared radiation from the surface of the material thereby providing improved identification of the material. Similar to the embodiment of the invention shown in FIG. 3, the infrared radiation sensing system **16** shown in FIG. 5 is located immediately off the discharge end **26** of the conveyor **14** so that transmitted infrared radiation signal **50** may pass through sample **28** for detection by the sensing system **16**. In alternate embodiments, rather than the transmission infrared radiation source **48** and sensing system **16** being located immediately off the discharge end **26** of the conveyor **14**, they may be positioned a minimal distance downstream from the discharge end **26** of the conveyor **14**. A minimal distance is from about one inch to about six inches. In another embodiment, a minimal distance is about two inches. In either embodiment, the conveyor **14** is not presented to the infrared radiation sensing system **16** as it was in previously existing units.

Still referring to FIG. 5, there is shown an embodiment of the present invention that uses a single processor system **46**, rather than a combination of a first processing system **18** and a second processing system **20** and that performs tasks similar to those performed by first processing system **18** and second processing system **20**. A single processor system **46** suitable for the current invention may be obtained from Dell, Round Rock, Tex. Such single processor systems **46** are known in the art and readily commercially available.

Disclosed herein is an embodiment of a method of sorting materials in order to overcome the above discussed disadvantages of the configuration shown in FIGS. 1 and 2, in addition to providing additional benefits. The method includes the use of a device having the infrared radiation sensing system **16** moved to a position off the discharge end **26** of the conveyor **14**. An infrared radiation source **12** (reflection infrared radiation source, shown in FIG. 3) has been developed that provides focus of the impinging infrared radiation **36** into a narrow band that does not strike the conveyor **14** and that illuminates items to be sorted within the sensing region. The ejection system **22** is positioned a short distance downstream from the sensing region. In certain embodiments of the present invention, a short distance is about six inches, so that items to be ejected travel only the 6 inches before they are ejected over the splitter **40** and segregated from the main material flow.

This method has several advantages over currently available sorting methods. First, as described above, the shorter travel distance **D** compared to the traditional method of using the device shown in FIG. 1 minimizes effects upon ejection accuracy due to changes in sample **28** speed with respect to conveyor **14** speed due to bouncing, rolling, and the like. The detrimental effect on ejection timing due to changes in speed gets worse over time since the sample **28** gets further and further away from the target arrival time at the ejection system

22. The short distance of the presently disclosed invention minimizes the time from detection to ejection, thus minimizing the detrimental effect.

Second, the short travel distance **D** provided in the currently disclosed method of using the device disclosed herein as compared to the traditional method of using the device shown in FIG. 1 minimizes effects upon ejection accuracy due to lateral motion of an item to be ejected. The time from detection to ejection is considerably shortened by using the device shown in FIG. 3, as compared to using the device shown in FIG. 1, which minimizes the amount of time that an item to be ejected strays out of its expected path before ejection.

Third, build up of foreign materials on the conveyor **14** do not interfere with the infrared radiation signals **38** being received by the infrared radiation sensing system **16** since the conveyor **14** surface is no longer presented to the infrared radiation sensing system **16**. Fourth, interference of the conveyor **14** surface with color determination of transparent items (e.g., PET bottles) is eliminated since the sample **28** being sensed is no longer on the conveyor **14** surface and instead is located off the discharge end **26** of the conveyor **14**. Fifth, the potential for fire resulting from the intense radiation from the infrared radiation source **12** is minimized since the infrared radiation **36** emanating from the source **12** is directed into the "free air" sensing region, which is off the discharge end **26** of the conveyor **14**. In the event the conveyor **14** stops, sample **28** will not stop suspended in air in the sensing region but will pass on through due to its intrinsic trajectory. Therefore, there will be no conveyor **14** surface or stationary sample **28** in the irradiated sensing region while the conveyor **14** is stopped or at any other time. Finally, another advantage to the method disclosed herein is the ability to add a transmission infrared radiation source **48** below the sample **28** feed stream as it discharges off the discharge end **26** of the conveyor **14**. In the examples shown in FIG. 1 and FIG. 2 it is not possible to add a transmission infrared radiation system for sensing at the same location along the sample **28** path of travel as is located the reflection infrared sensing system **16** since the conveyor belt is in the way.

This patent application expressly incorporates by reference all patents, references, and publications disclosed herein.

Although the present invention has been described in terms of specific embodiments, it is anticipated that alterations and modifications thereof will no doubt become apparent to those skilled in the art. It is therefore intended that the following claims be interpreted as covering all alterations and modifications that fall within the true spirit and scope of the invention.

What is claimed is:

1. A method of sensing and sorting materials according to composition, comprising:
 providing a sample;
 placing the sample on a conveyor having a discharge end;
 placing the sample in an infrared radiation sensing region, wherein the infrared radiation sensing region is located immediately off the discharge end of the conveyor;
 irradiating the sample to be sorted with infrared radiation in the sensing region;
 detecting infrared radiation signals reflected off the sample while the sample is located immediately off the discharge end of the conveyor;
 analyzing the infrared radiation signals to determine composition of the sample;
 energizing at least one air ejector of an air ejection array, wherein the air ejection array is located immediately downstream from the infrared radiation sensing region.

9

2. The method of claim 1, wherein the infrared radiation sensing region is located at a minimal distance from the discharge end of the conveyor.

3. The method of claim 1, wherein the air ejection array is located at a minimal distance downstream from the infrared radiation sensing region.

4. The method of claim 1, further comprising detecting infrared radiation signals transmitted through the sample while the sample is in the sensing region.

5. A sorting device for sorting materials according to composition, comprising:

an infrared radiation source;

a conveyor, wherein the conveyor has a discharge end;

an infrared radiation sensing system positioned to receive and detect infrared radiation reflected off a sample while the sample is located immediately off the discharge end of the conveyor and is irradiated with infrared radiation from the infrared radiation source;

a first processing system operationally connected to the infrared radiation sensing system so that the detected infrared radiation signals are analyzed to determine composition of the sample;

an ejection system positioned immediately downstream from the infrared radiation sensing system;

a second processing system operationally connected to the ejection system so that sample having certain composition may be ejected out of the flow path by the ejection system;

a receiving station positioned to receive ejected sample.

6. The device of claim 5, wherein the infrared radiation sensing system is located a minimal distance downstream from the discharge end of the conveyor.

10

7. The device of claim 5, wherein the ejection system is located a minimal distance downstream from the infrared radiation sensing system.

8. The device of claim 5, wherein the first processing system and the second processing system are combined into a single processing system.

9. A sorting device for sorting materials according to composition, comprising:

an infrared radiation source;

a conveyor, wherein the conveyor has a discharge end; an infrared radiation sensing system positioned to receive and detect infrared radiation reflected off a sample while the sample is located immediately off the discharge end of the conveyor and is irradiated with infrared radiation from the infrared radiation source;

a processing system operationally connected to the infrared radiation sensing system so that the detected infrared radiation signals are analyzed to determine composition of the sample;

an ejection system operationally connected to the processing system so that a sample having a certain composition may be ejected out of the flow path, wherein the ejection system is positioned immediately downstream from the infrared radiation sensing system;

a receiving station positioned to receive ejected sample.

10. The device of claim 9, further comprising a transmission infrared radiation source positioned so that the infrared radiation sensing system receives and detects infrared radiation transmitted through the sample while the sample is located immediately off the discharge end of the conveyor and is irradiated with infrared radiation from the transmission infrared radiation source.
